COMPRESSOR

Milton S. Shepherd and Francis C. Wiley, Salt
Lake City, Utah, assignors of one-third to Louis
A. Roser, Salt Lake City, Utah

Application, February 23, 1932, Serial No. 594,443

3 Claims. (Cl. 230—190)

Our invention relates to compressors and has for its object to provide a new and efficient fluid compressor for use primarily in refrigeration machines.

5 A further object is to provide a compressor which has a new type of noiseless intake and exhaust valves and which valves are more efficient than those used heretofore, giving greater compressibility to any type of compressor when used 10 therein.

A still further object is to provide a simplified construction of intake and exhaust valves in which air cushions and air pressure are used to stabilize the operation of the valves and to make 15 them noiseless in operation.

A still further object is to provide a construction of intake or suction valve which is so built as to have longer life and to prevent "pounding off" of the lock nut thereon.

20 A still further object is to provide a compressor which has the suction valve so constructed that when starting no load is carried until the compressor has attained sufficient speed to close the suction valve in the piston.

25 These objects we accomplish with the device illustrated in the accompanying drawings, in which similar numerals and letters of reference indicate like parts throughout the several views and as described in the specification forming a part of this application and pointed out in the appended claims.

In the drawings in which we have shown the best and most preferred manner of building our invention,

35 Figure 1 is a vertical diametrical section of a compressor piston and cylinder with our discharge and suction valves used in connection therewith.

40 Figure 2 is a vertical diametrical section through the discharge valve on line 2—2, of Figure 3.

Figure 3 is an inverted plan view of the top portion of the valve cage.

45 Figure 4 is a side elevation of Figure 3.

Figure 5 is a plan view of the valve seat formed in the lower half of the cage.

Figure 6 is a side elevation of Figure 5.

Figure 7 is a vertical diametrical section of the 50 discharge valve on line 7—7 of Figure 3.

Figure 8 is a vertical diametrical section of the suction valve and cage with the spring removed.

Figure 9 is a similar section to that shown in Figure 8 with the valve removed.

55 Figure 10 is an outside elevation of the cage.

Figure 11 is a plan view of the suction valve cage.

Figure 12 is a diametrical section of a compressor cylinder and piston showing a modified form of discharge valve with a plurality of valves mounted in the discharge valve cage with one valve shown sectioned and the other in elevation.

Figure 13 is an inverted plan view of the base of the discharge valve cage showing four openings therein.

5

10

Figure 14 is a plan view of Figure 13.

Figure 15 is a vertical diametrical section of one of the individual valves.

Figure 16 is a side elevation of the ring base of the individual valve housing.

15

Figure 17 is a plan view of Figure 16.

In the drawings we have shown our discharge and suction valves as carried in a cylinder A, and in the piston B, of any of the conventional types of compressors and with the discharge valve C carried in a cage 1, said cage composed of two members 2 and 3, secured together by bolts 4, with the lower member 3 formed with a centrally disposed valve seat 5. A flange 6 and bosses 7 space the member 3 from the member 2. The cylinder wall 8 of the cylinder A is provided with a step cut 9 into which the member 3 sets and the member 2 is carried in alignment with the member 3 superimposed thereover. The top side of the member 2 of the cage is provided with an annular ring flange 10, to hold a pressure spring 11 centrally thereover and the cylinder head cover 12 is then placed thereover and secured by suitable bolts with the pressure of the spring holding the assembled cage in place in the cylinder. The upper member 2 of the cage is composed of a block 13 having an extension or boss 14 formed on the top side and having a central threaded perforation therethrough; in which a plug 14a is screwed.

25

Figure 14 from the bottom side of the member 2 we provide a cylindrical bore 15 and in the face of the block we provide an enlarged bore 16 with a closure guide plate 17 fitting into the bore 16 to close the opening of the bore 15. The plate 17 is centrally perforated to receive the valve stem 18 and a piston 19 is carried in the bore 15 above the plate 17 with the end of the stem 18 threaded into the piston and secured thereto by a locking screw 20. A spring 21 is carried over the top of the piston 19 to normally hold the piston down to the bottom of its stroke. The valve stem 18 has a valve 22 formed on the lower end, said valve to seat in the valve 5.

30

Figure 15 is a vertical diametrical section of the discharge valve on line 7—7 of Figure 3. Figure 16 is a side elevation of Figure 5. Figure 17 is a vertical diametrical section of the 50 discharge valve on line 7—7 of Figure 3. Figure 18 is a vertical diametrical section of the suction valve and cage with the spring removed. Figure 19 is a similar section to that shown in Figure 8 with the valve removed. Figure 20 is an outside elevation of the cage.

35

Figure 21 is a plan view of the valve seat formed in the lower half of the cage. Figure 22 is a side elevation of Figure 5. Figure 23 is a vertical diametrical section of the discharge valve on line 7—7 of Figure 3. Figure 24 is a vertical diametrical section of the suction valve and cage with the spring removed. Figure 25 is a similar section to that shown in Figure 8 with the valve removed. Figure 26 is an outside elevation of the cage.

40

Figure 27 is a plan view of the valve seat formed in the lower half of the cage. Figure 28 is a side elevation of Figure 5. Figure 29 is a vertical diametrical section of the discharge valve on line 7—7 of Figure 3. Figure 30 is a vertical diametrical section of the suction valve and cage with the spring removed. Figure 31 is a similar section to that shown in Figure 8 with the valve removed. Figure 32 is an outside elevation of the cage.

45

Figure 33 is a plan view of the valve seat formed in the lower half of the cage. Figure 34 is a side elevation of Figure 5. Figure 35 is a vertical diametrical section of the discharge valve on line 7—7 of Figure 3. Figure 36 is a vertical diametrical section of the suction valve and cage with the spring removed. Figure 37 is a similar section to that shown in Figure 8 with the valve removed. Figure 38 is an outside elevation of the cage.

50

Figure 39 is a plan view of the valve seat formed in the lower half of the cage. Figure 40 is a side elevation of Figure 5. Figure 41 is a vertical diametrical section of the discharge valve on line 7—7 of Figure 3. Figure 42 is a vertical diametrical section of the suction valve and cage with the spring removed. Figure 43 is a similar section to that shown in Figure 8 with the valve removed. Figure 44 is an outside elevation of the cage.

55

to enter the bore 15 above the plate 17 said pressure to prevent noise in the valve when it is closing.

The plate 17 may be dispensed with and the fluid pressure be directed entirely against the lower side of the piston 19 eliminating parts in construction and at the same time having the pressure against the piston to use the involved pressure to act against the closing of the piston 10 to counterbalance the pressure on the top side of the valve making the valve more noiseless when closing.

The suction valve D is carried in a cage 25 which cage is cylindrical in form and provided 15 with a flange 26 therearound adapted to fit into a socket 27 in the piston head E, and be secured therein by placing an annular ring 28 thereabove resting on the flange 26 and fitting into an annular step 29 in the piston head. The ring is secured by spaced apart tap screws 30. The bottom 20 end of the cylindrical cage 25 is formed into a support bearing 31 extending up into the bore of the cylinder to support the valve stem therein and the lower end of the block is provided with an enlarged bore 33 in which a piston 32 is carried, said 25 piston being secured onto the lower end of the valve stem 24 by threads and by a locking bolt 35. A small port 36 is bored through the side wall of the block into communication with the chamber 30 37 above the piston 32 in the bore 33. This is to allow air to be forced from the chamber when the valve is opening, but the port is bored into the chamber a short distance from the end thereof so that the piston when rising in the chamber moves 35 freely until just before it reaches the end of its stroke and the end of the stroke will be cushioned by the compression of the air in the chamber 37 above the piston 32. The top inner edge of the block 31 is inwardly chamfered to provide an oil 40 retaining well to catch and retain oil for lubrication of the valve stem. Ports 29 through the side walls of the cage 25 provide air passage thereinto from the space surrounding the piston in the cylinder A.

45 The piston B of the device is of the usual compressor type having a head and skirt joined together by vertical struts leaving an air space between the skirt and head which space is joined into the circuit of the system in which the compressor is being used or to the atmosphere if air is being compressed.

50 For large compressors where high pressure is required we have provided a multiplicity of discharge valves in the discharge cage as shown in Figures 12, 13, 14, 16 and 17 of the drawings.

55 The cage is made of a head 40 and base 41 carried in the cylinder step cut as is the other discharge cage. The base 41 is provided with spaced apart sockets 42 with a valve seat 44 formed in the bottom of the socket and with the ports 43 passing down through the base. Within the sockets 42 we then place annular port rings 45, said rings being provided with ports therethrough to allow fluid pressure to pass therefrom. The top 60 inner side of the rings is step cut and into the step cut we place circular plates 46, said plates having a flange 47 thereon the diameter of the step cut to fit thereinto with the balance of the plate of smaller diameter to fit up into cylindrical caps 48. The caps 48 have the lower edge flanged to fit onto the top of the rings 45 and the flange 47 to hold the rings and plate together and the top end of the caps is closed, but provided with a threaded opening medially therein 65 in which a closure plug is screwed. Valves 50

are carried in the rings with the valve stem extending up through a bore 51 in the plate 46. The top end of the valve stem carries a piston 52 with a spring 53 carried over the top of the piston within a socket in the plug 49. The piston 52 is operated within the cap and a milled cut 54 is provided in the bore of the plate 46 to allow air pressure to enter the port 55 above the plate and under the piston to make the closing of the valve quiet. The valves are normally held 10 in the valve seats 44 by the pressure of the springs 53. Each valve is set in place and the caps placed thereover and the top head 40 is then placed thereover resting on the top end thereof and the large spring 56 is then placed thereover and the cylinder head 57 secured holding the entire device securely in place by spring pressure.

15 The operation of the device is as follows:

The piston is drawn down by the crank shaft (not shown) and in being drawn down the valve 20 D in the piston head is opened, letting fluid into the cylinder above the piston head. The piston is then forced up and this compresses the fluid in the cylinder above the head until sufficient pressure has been created to open the valve C 25 and allow the fluid to be forced into the space in the cylinder above the valves and out to any desired source through the pipe line indicated by the dotted lines a in Figure 1. New fluid is at the same time being drawn into the cylinder 30 through the pipe line indicated by dotted lines b in Figure 1. This operation is continued.

35 The pressure created in that space above the valve seats in the cylinder head is passed through the milled cut into the cylinder 15 above the plates 17 thereby creating a pressure against the piston 19 holding the valve 22 from seating hard enough to create a vibration or noise.

40 In the form of compressor shown in Figure 12 we have shown the plurality of valves and the piston compresses the fluid forcing the valves 50 open allowing the pressure to pass out to the desired destination. The milled cuts 54 in the plates 46 allow the pressure to enter the cap 48 under the piston 52 to hold the valves from making noise when they close.

45 Having thus described our invention we desire to secure by Letters Patent and claim:

1. A discharge valve comprising a cage; a valve seat in the lower end of the cage, a cylinder in the upper end of the cage; a valve adapted to open or close said seat; a piston carried on the valve stem within said cylinder; a plate closing the lower open end of the cylinder with the valve stem operable therethrough; a milled cut through 55 said plate adjacent the valve stem; and a spring carried in the cylinder pressing on the top of the piston to normally hold the valve seated.

2. A discharge valve for compressors comprising a cage having a valve seat in the lower portion and a cylinder in the upper portion; a valve carried in said cage; a piston operating in the cylinder connected to the valve by the valve stem; and means to introduce fluid into the cylinder under said piston to use the involved fluid to prevent the valve from vibration and sudden closing.

3. In a multiple discharge valve assembly for compressors, the combination of a cage mounted in the head of a compressor cylinder, said cage formed in two sections formed to fit together; valve seats formed in the lower section with ports leading from the space above the valve seats through the side walls of the lower section, cylindrical valve chambers carried in the 75

upper section; plates carried in each valve chamber to close the opening thereinto with an opening through the plate to receive the valve stem and with milled cuts through one edge of said openings to allow for passage of fluid therethrough; valves carried above each seat to normally close the seat with the valve stem extending up into the chamber thereabove through

the opening in said plates; a piston carried on each valve stem operable within said chamber to modify and cushion the action of the valves; and springs carried on said pistons within said chambers to normally hold themselves seated.

5
